(57) **CLAIM**

The ornamental design for a bag dispenser and container for dog waste disposal, as shown and described.

DESCRIPTION

FIG. 1 is a front elevational view of a bag dispenser and container for dog waste disposal showing my new design; FIG. 2 is a rear elevational view thereof; FIG. 3 is a side elevational view thereof; FIG. 4 is a top plan view thereof; FIG. 5 is a bottom plan view thereof; and, FIG. 6 is a bottom front perspective view shown in use. The broken lines in FIG. 6 have been provided for the purpose of illustrating environment that forms no part of the claimed design.
